[57] CLAIM

The ornamental design for a golf club head, as shown
and described.

DESCRIPTION

FIG. 1 is a front elevation view of a golf club head
showing our new design;

FIG. 2 is a left side elevation view thereof;

FIG. 3 is a top plan view thereof;

FIG. 4 is a bottom plan view thereof;

FIG. 5 is a rear elevation view thereof;

FIG. 6 is a right side elevation view thereof; and,
FIG. 7 is a cross sectional view thereof taken in the
direction of line 7—7 of FIG. 3.

The broken line showing of a shaft, fragmentary shown,
is for illustrative purposes only and forms no part of the
claimed design.

FIG. 1
